CAN LIFTER

Joe B. McMillan, La Conner, Wash.

Application August 2, 1937, Serial No. 156,927

16 Claims. (Cl. 294—87)

My invention relates to devices for engaging and lifting groups of articles, such as cans. The principles of this invention may be embodied in devices for lifting other articles which can be grouped, for instance bottles. While I shall refer to it as a can lifter, it will be understood that no restriction is intended as to the manner of use nor to the articles with which it is intended to be used. It will be found useful for and it is my intention to protect its use in conjunction with any articles to which it is adapted, particularly articles of cylindrical shape which are commonly grouped, preferably in a generally rectangular pattern, and which it may be desired to lift and transport, usually through short distances, in the group arrangement.

My invention has been particularly devised to facilitate the packing of shipping cases for canned goods. This operation is generally performed by hand, the cases (with cans of the sizes most generally used) being packed in two layers, twelve cans in each layer, and each layer in a generally rectangular pattern or grouping of three rows of four cans each. As a result of this grouping there are two inside cans, and the remaining ten cans all form part of the outside of the general pattern. It is an object of the present invention to provide means which need engage only the outside cans of such a group, which will segregate such a group, including the two inside cans, from a larger grouping, without disturbance of the grouping, which will lift these twelve cans by inward pressure upon the outside cans and without any engagement of the inside cans except by the adjacent walls of the adjoining cans, thereby permitting the entire group of twelve to be lifted, transported, set down within a packing case, and released.

It is a further object to devise a can lifter of the general character indicated above, the elements of which lie wholly within the general rectangular pattern of the cans, and which will therefore fit within the packing case without any engagement of the walls of the case by the lifting means, to the end that there will be no interference occasioned by such engagement, and to the further end that cases may thus be packed twelve cans at a time, and in a rapid and accurate manner.

It is a still further object to provide a can lifter of this type which may be so arranged as to lift two or more such layers of cans, each layer having cans similarly grouped, to the end that an entire case may be packed in one operation.

It is a further object to provide such a can lift-

ing device which will readily engage and disengage the cans, and which when engaging them will do so in a manner which distributes inward pressure over considerable areas of the cans, to the end that they will not be deformed, and to the further end that the labels, if applied, will not be disturbed nor marred.

Speaking more generally, it is an object to devise a can lifter which will segregate, engage, and lift a group of cans without the necessity of individually and positively gripping each such can, but which will effect the lifting action by inward pressure upon the outer side only of the outermost cans, pressing them inwardly into lifting engagement with the adjacent sides of adjoining cans, for instance cans in adjoining rows, and regardless of whether the grouping is in rows, in a rectangular, circular, or other pattern, or whether there are or are not inside cans.

Among other objects are to provide a device by which the normal lifting action will effect the gripping of the cans; to provide gripping means which are adapted to the application of a sufficiently powerful force; to provide for ready disengagement of the cans when desired; to provide adjustments, for instance, to adapt the device to hands of different size or span of grip; and in general to provide a device which is rugged and reliable, and yet sufficiently light.

My invention comprises the novel parts, and the novel combination and arrangement thereof, as shown in the accompanying drawings, and as will be hereinafter more fully disclosed and defined.

In the accompanying drawings the principles of my invention are shown embodied in two illustrative forms.

Figure 1 is a general plan view, with parts broken away and other parts omitted, illustrating my invention in a preferred form, in association with a group of cans and a packing case to receive such cans.

Figure 2 is in part an elevation and in part a section, the view in general being along the line 2—2 of Figure 1.

Figure 3 is a transverse section substantially on the line 3—3 of Figure 1.

Figure 4 is an axial section along the upright post, taken at right angles to the sectional portion of Figure 2.

Figure 5 is a fragmentary view similar to Figure 3, illustrating a modified form of the invention.

Canned goods are generally handled in masses, in which the cans are collected in large groups of

a number of rows and in effect an endless number of cans in each row. The device of the present invention segregates a required number of cans, for example twelve, from the larger group, 5 lifts them, and enables their transportation and deposit within a packing case, as a group. Later if it is desired to lift them as a group from the packing case, the device may be employed in this manner, fitting down into the packing case, without 10 interference with either the cans or the packing case, engaging the cans and enabling them to be lifted from the case. In the preferred form the cans are lifted in groups of twenty-four, the usual capacity of a shipping case, arranged in two layers or groups of twelve cans each. Naturally the feasibility of this will depend to a considerable degree upon the weight, height, and size of the cans, so that it is not outside the scope of my invention to employ a device which will 15 lift a single layer only or more than two layers, or a device which will lift the cans in groups of more or less than twelve, or arranged in patterns other than rectangular.

The basis of the invention lies in the provision 20 of gripping means such as the fingers 1, which are of a size and shape to extend down alongside the cans within the valleys between each two adjoining cans in the group, and therefore lying wholly within the general rectangular pattern of the group, and to provide suitable means to press these fingers inwardly when the gripping action is desired. They will usually be of metal, and while I have not found it necessary to face them with frictional material, this can be done if desired. 25 Their length is arranged to grip the number of layers desired, and there are sufficient fingers to engage in each outside valley of the group of the pattern which is to be lifted. In a can lifter for use in packing the ordinary packing case ten such fingers are employed, and it will be observed that they engage only within the valleys between each two outside cans. If they are to engage a second layer they are preferably extended inward slightly more at their lower end than at their upper end, so that the 30 gripping action is substantially confined to the engagement with the lowermost group or layer, and their engagement with the upper group or groups is chiefly a restraining action to prevent outward spreading or sliding of the cans in the upper layers. They are preferably relieved, as indicated at 10 and 11, to straddle the top and bottom bead, and while it is the inward pressure of the fingers engaging the sides of the cans that 35 is chiefly relied upon to effect the lifting, the relieved portions 10 and 11, especially the former, may at the same time grip the circumferential edges of the beads, and effect lifting engagement, since this is the least compressible part of the can, and the shoulder formed by the recesses 10 and 11 may to some extent engage beneath the flange of the bead. By engaging the sides of the cans over a considerable length, the pressure is so distributed that the can walls 40 are not deformed.

Preferably a number of such flanges along each of two opposite ends or sides of the group are secured together by connecting them rigidly to strips 13 and 14 for conjoint movement inwardly and outwardly of the group. Thus the strips 13 along the two longer sides of the group carry three such fingers 1, and the strips 14 carry two. Since it is not desirable to permit the fingers to extend outwardly around the corner cans sufficiently to encompass a diagonal diameter of such

corner cans, because this would bring a part of such fingers outside of the general rectangular pattern of the group, it is preferable that additional restraining means or fingers 12 be provided, engaging the corner can at the corner of the group, and these fingers 12 may likewise be secured to the strips 13. They restrain the tendency of the two fingers 1, which press into the two valleys at opposite sides of such corner cans, to press the corner cans outwardly, and thus 10 the corner can is preferably held at three points, although it will be evident, if the fingers 1 which engage this corner can extend sufficiently far as to encompass the diagonal diameter of the can, the restraining finger 12 will not be needed. It 15 will be observed by reference to Figure 1 that the fingers 1 and 12 lie wholly within the rectangular pattern formed by the grouping of the cans, and within the walls of the packing case C, so that no interference results, yet the cans 20 are closely confined within the packing case.

As will now be evident, various means may be employed to effect the desired inward and outward movement of the fingers. The means preferred by me is illustrated in Figures 1 to 3, inclusive. A plate 2 constitutes the base for the device, and upon this base are secured sleeves 22 receiving rods 21 which are secured to the strips 13 or 14. If these are non-circular in cross section one only may be needed for each 30 strip, but preferably additional guide rods and sleeves are provided, as indicated at 22 and 23, respectively. The rods 21 and sleeves 22 are substantially centrally disposed, and to each of them is connected lever mechanism or the like to draw 35 the rods 21 and consequently the strips 13 or 14 inwardly.

A post 3 is carried by the plate 2 and projects upwardly therefrom, and upon this post, which is preferably non-circular in cross section, is slidably received a slide 30. Lever arms 24 are pivoted at 25 upon the post 3, and their lower arms are connected, as by links 26, to the inner end of the rods 21. To the upper arm of each lever 24 is connected an inwardly and downwardly inclined link 27 in the nature of a toggle link, which is pivotally connected at 28 to the slide 30. The slide 30 is provided with a laterally extending lifting handle 31, and preferably arms 32 extend laterally from the upper end of the post 3 above the lifting handle 31. A spring 33, reacting between the slide 30 and a collar 34 adjustable lengthwise of the post 3, tends to move the slide downwardly, and in a direction to move the fingers 1 outwardly. A stop collar 39 on the post, engageable by the slide, limits downward movement of the slide, and spreading of the fingers, and may be adjustable along the post, if desired.

Engagement of the lifting handle 31, as in lifting, accompanied, if necessary, by a slight squeezing between the handle 31 and the arms 32, overcomes the tendency of the spring 33 to spread the fingers, and draws the fingers inwardly, a powerful gripping action being secured by the toggle arrangement of the inclined links 27. 65 With the fingers thus drawn inwardly the cans are gripped and the entire group may be transported thus. Though there is no positive engagement by the fingers of the innermost cans of the group, the outermost cans are pressed inwardly into such engagement with the inside cans as to cause them to be lifted in their proper relationship and position with respect to the outside cans.

The collar 34, as shown in Figure 4, is adjust- 70

able lengthwise of the post 3 in order to adjust the compression pressure of the spring 33. A set screw 35 has its inner pointed end engageable in any one of a series of depressions 38 in the post 3 to accomplish this adjustment. Furthermore the spacing between the lifting handle 31 and the arms 32 may be adjusted in order to accommodate the span of grip of an individual's hands, and this is conveniently accomplished by securing a nut 36 to the arms 32, the upper end of the post being threaded, and the adjustment being accomplished in this way, parts being held in adjusted position by a lock nut 37.

It is not essential, though preferable, that the fingers 1 have rectilinear inward and outward movement. They may be pivotally mounted, as shown in Figure 5. Here the strip 13, carrying the several fingers 1, is pivotally mounted at 15 upon the plate 2, through the medium of a lever 16, to the upper end of which is connected a link 17, in turn pivotally connected at 18 to the lower end of the slide 30. Upward movement of the slide effects inward swinging of the fingers 1 in this arrangement.

25 While the operating mechanism described is that which I now prefer to use, it being simple, adequately powerful, and rugged, as well as being adjustable as necessary, yet various forms of operating mechanism may be employed to effect 30 movement and gripping of the fingers in accordance with the principles of my invention disclosed at the outset of this specification.

What I claim as my invention is:

1. Mechanism to lift a group of cans or the like, in which group one or more cans are surrounded by other cans, comprising a support, a plurality of fingers carried by and depending below said support, and arranged in a pattern to enclose the group, and to engage the side of each 40 outside can of the group, only, and means to press all said fingers inwardly, thereby pressing the outside cans into firm engagement with the inside cans.

2. Mechanism to lift a group of cylindrical cans or the like, in which group one or more cans are surrounded by other cans, comprising a plurality of fingers disposed in a pattern to surround the group and to engage the side of each outside can, only, a lifting handle, and means operatively connecting said lifting handle to the fingers, in such manner that upward movement of the lifting handle effects inward movement of all the fingers simultaneously, thereby pressing outside cans into firm engagement with the inside cans.

3. Mechanism to lift a group of cylindrical cans or the like disposed in a plurality of rows, comprising a plurality of fingers disposed in a pattern to engage the outer side only of each outer can, and to engage each corner can of the group outside of a diameter, and means to press said fingers inwardly, thereby pressing the inner side of each outside can into lifting engagement with the adjacent side of an adjoining can.

4. Means to lift a group of cans or the like disposed in a rectangular group of a plurality of rows, comprising fingers disposed in a rectangular pattern to engage the outer side only of each outside can, within the valley between each two adjoining cans, whereby each such finger engages two cans, means disposed at the corners of such rectangular pattern of the fingers, in position to engage the outer corner of each corner can of the group, to restrain outward movement thereof, and means to press all said fingers in-

wardly from each side and end of the group, thereby pressing the inner side of each outside can into firm engagement with the adjacent side of an adjoining can.

5. Means to lift a group of cylindrical cans or the like disposed in a plurality of rows in a generally rectangular pattern, comprising a plurality of fingers, one disposed in each valley between each two outside cans, only, to engage the side of such cans, and the several fingers arranged in a rectangular pattern, means disposed at the corners of such rectangular pattern of the fingers to engage and restrain the outside corner of each corner can, and means to press all said fingers inwardly from both ends and both sides of the group, thereby pressing the inner side of each outside can into lifting engagement with the adjacent side of an adjoining can, said fingers and said corner-engaging means being disposed substantially entirely within the rectangular pattern tangent to the outside cans of the group.

6. Means to lift a group of cans or the like disposed in a plurality of rows in a generally rectangular pattern, comprising fingers disposed in each valley between two cans in the rows along two opposite outer sides of the group, means to press said fingers inwardly, thereby pressing the inner side of each such can into lifting engagement with the adjacent side of a can in the adjoining row, and means engageable with the end cans of each row to restrain movement thereof of lengthwise of the rows.

7. Means to lift a group of cans or the like disposed in a plurality of rows in a generally rectangular pattern, comprising fingers disposed in each valley between two cans in the rows along two opposite outer sides of the group, means to press said fingers inwardly, thereby pressing the inner side of each such can into lifting engagement with the adjacent side of a can in the adjoining row, and means engageable with the end cans of each row to restrain movement thereof of lengthwise of the rows, said latter means and said fingers being disposed substantially entirely within the rectangular pattern of the group of cans.

8. Means to lift a plurality of closely grouped cans or the like, comprising fingers of a length equal to an appreciable part of the height of the cans, disposed in the valleys between each two adjoining outermost cans, only, means guiding said fingers for movement into and from the bottoms of such valleys, thereby, in conjunction with adjoining fingers, to press said cans inwardly and to press their inner sides into lifting engagement with the adjacent side of an adjoining can, and means so to move such fingers.

9. Means to lift a plurality of closely grouped cans or the like, comprising a plate disposed above the group of cans, fingers depending from said plate of a length equal to an appreciable portion of the height of the cans, and shaped to lie wholly within each valley between two adjoining outermost cans, means carried by said plate guiding said fingers for movement into and from the bottoms of such valleys, and means carried by the plate and operable from above the group to effect such movement, thereby to press the inner side of each can into lifting engagement with the adjacent side of an adjoining can.

10. The combination of claim 9, including a strip joining a plurality of fingers for movement, and in which combination the guide means are formed as cooperating rods and sleeves, one car-

ried by the strip and the other by the plate, for rectilinear movement of the fingers.

11. The combination of claim 9, including a strip whereon a plurality of fingers are rigidly secured, and in which combination the guide means are formed as a pivot pin carried by the plate and an arm pivoted thereon and secured to the strip, for slight swinging movement of the fingers.

10 12. Means for lifting a plurality of closely grouped cans or the like, comprising a plate disposed above the group of cans, fingers depending from the plate in position to engage the outer sides, only, of only the outermost cans, a post 15 upstanding from the plate, a slide movable along the post towards and from the plate, a lifting handle connected to said slide, and means operatively connecting the slide to the fingers, to draw the latter inwardly into lifting engagement with 20 the cans by upward movement of the slide.

13. Means for lifting a plurality of closely grouped cans or the like, comprising a plate disposed above the group of cans, fingers depending from the plate in position to engage the outer 25 sides, only, of only the outermost cans, a post upstanding from the plate, a slide movable along the post towards and from the plate, a lifting handle extending laterally from the slide, arms parallel to and above the handle, projecting from 30 the post, spring means tending to separate the handle and said arms, and means operatively connecting the slide to the fingers, to draw the latter inwardly into lifting engagement with the cans by upward movement of the slide.

35 14. The combination of claim 12, including strips on each of which a plurality of fingers are

rigidly secured, means carried by the plate guiding said strips for rectilinear inward and outward movement, thus to draw the fingers into lifting engagement with the cans, or to release them, an upright lever arm for each strip pivoted 5 between its ends on the post, its lower end being operatively connected to its corresponding strip, and a downwardly and inwardly inclined link connecting the upper end of each lever to the slide, whereby upward movement of the latter 10 effects powerful inward movement of the strips and their fingers.

15. Means to lift a plurality of closely grouped cylindrical cans or the like, comprising a plate disposed above the group of cans, a plurality of 15 fingers each supported from and depending from the plate, and forming a plurality of groups of fingers each of a size and shape to encompass one side of the group of cans, and in the aggregate surrounding the entire group of cans, each 20 of such fingers being positioned to engage an outer side only of an outside can, and means to compress all of said groups of fingers inwardly simultaneously, to compress all the cans of said group into firm adherence as a group.

16. Mechanism to lift a group of cylindrical cans or the like disposed in a plurality of rows, comprising a plurality of fingers disposed in four or more groups in a pattern to surround the group of cans and to engage the outer side only of each 30 outside can, and means to press said groups of fingers simultaneously inwardly, thereby pressing the inner side of each outside can into firm engagement with the adjacent side of an adjoining can.

35 JOE B. McMILLAN.
